UNITED STATES PATENT OFFICE

GEORGE F. EGAN, OF JERSEY CITY, NEW JERSEY

SWITCH

Application filed December 18, 1925. Serial No. 76,240.

The present invention relates to improvements in signalling devices, and has for an object the provision of improved means for giving a visible or audible signal, or both, when, for instance, a vehicle buffer strikes an object. The invention has for a further object to give a signal when the buffer is collapsed incident to the striking of an object, whereby drivers of other vehicles may be apprised of the accident and given opportunity to bring vehicles operated by them to a stop or direct them out of the way of the stalled vehicle.

Further objects of the invention are to make certain improvements in the buffer, whereby a circuit closer may be actuated, and in so constructing the circuit closer as to cooperate with the deformable buffer. The invention may be installed in connection with a signal lamp or annunciator, or both, and with the usual battery of an automobile.

With the foregoing and other objects in view the invention will be more fully described hereinafter, and more particularly pointed out in the claims appended hereto.

In the drawings, wherein like symbols refer to like or corresponding parts throughout the several views:

Figure 1 is a top plan view of a vehicle equipped with a buffer and signal device embodying my improvements;

Figure 2 is a longitudinal section taken on the line 2—2 in Figure 1; and

Figure 3 is an enlarged fragmentary perspective view of a circuit closer in closed position.

Referring more particularly to the drawings, 4 designates generally the chassis of a vehicle shown as mounted upon rear wheels 5 and front wheels 6. At 7 is indicated an engine in dotted lines, and at 8 a radiator. A storage battery is represented at 9.

A signal lamp 10 is shown as mounted at the rear of the vehicle and such lamp will preferably have a red lens with the word "Stop" in transparent letters. The lamp 10 may be illuminated when the buffer 11 in the front of the vehicle strikes a person or object with such force as to be deflected back-

wardly, for instance to the dotted line position shown in Figure 1.

The buffer is shown as of a bowed or curved construction transversely of the vehicle with the convex side of the buffer presented outwardly whereby a deflection may take place toward the vehicle in an effort to straighten the curved buffer when the buffer encounters an object. The ends 12 and 13 of the buffer are shown as returned inwardly upon the bowed portion and as spaced from the bowed portion substantially parallel therewith. Connecting portions 14 and 15 permit the buffer to flex not only as to the bowed main portion 11, but also as to the ends 12 and 13. The buffer will preferably be of some flexible material, as a tempered steel. The ends 12 and 13 are shown as brought inwardly and turned rearwardly, the rearward extremities 16 and 17 being shown as fitted against extension frames 18 and 19 and bolted or otherwise secured thereto.

Abutments 20 and 21, preferably rounded, are shown as made between the ends or arms 12 and 13 and the extremities 16 and 17. These abutments do not move appreciably on account of the fixed position of the extremities 16 and 17 and consequently they form stops against which the outer bowed main portion of the buffer 11 may strike when deflected or deformed. The greater the deflection the more will the buffer part 11 spread out against greater areas of the arms 12 and 13 and the shock will thus be reduced and compensated. The central portion of the buffer 11 is shown as provided with a lug 22 adapted to receive the outer end of a rod 23, shown as slidably mounted in appropriate portions of the chassis. The rear end of the rod 23 is shown as coupled to a contact member 24 which may slide through an inverted substantially U-shaped guide 25 shown as mounted on a cross beam 26 and affixed thereto by appropriate fastenings. In the upper closed portion of the guide 25 a flat spring 27 is shown, the intermediate portion of which is affixed as by fastenings 28 to the guide 25. The free ends of the spring 27 are shown as projecting to both

sides of the guide and as bent downwardly and upwardly. These free ends play upon the upper surface of the contact member 24 and urge this contact member downwardly. 5 The rear end of the contact member 24 is shown as provided with a downwardly and forwardly projected hook 29, the lower edge of which is shown as of small area. The hook 29 normally rests upon the upper surface of a block of insulating material 30 shown as carried upon the companion contact member 31. Both contact members may be in the nature of flat metallic strips of appropriate length and width. 10 15 The contact member 24 is shown as disposed at an elevation above the contact member 31, and the contact may be made by the lower edge of the hook 29 when the parts are in the position shown in Figure 3. The rear end of the insulating block 30 is shown as beveled downwardly and inwardly to accord with the formation given the hook 29 in order that the hook may catch behind the block when the contact member 24 is moved 20 rearwardly to a sufficient extent to permit the hook to move off the block. The spring 27 will force the contact member and hook downwardly. The lower contact member 31 is shown as fixed, as by the fastenings 32, to a cross beam 33. Another cross member 34 25 may be used to support the forward end of the contact member 31, which carries the insulating block 30, and which sustain a certain thrust when the contact members are engaged. 30 35

The lamp 10 is shown as connected to a battery by a lead or conductor 35 and with the lower contact member 31 by a lead or conductor 36. The other terminal of the battery 9 may be grounded on the buffer frame by a lead 37, which thereby establishes a closed circuit when the contact members 24 and 31 are brought together.

In the operation of the embodiment of the invention shown in the drawings, the parts are in the position indicated in Figures 1 and 2 with the hook 29 of the movable contact member 24 riding upon the upper surface of the insulating block 30. The buffer 11 assumes the normal full line position, and the circuit is open in the normal condition of the parts.

Should a person or object be struck by the buffer 11 the reaction will cause the bowed front portion of the buffer to deflect rearwardly and with it the rod 23 will be pushed rearwardly. The rod will push before it the contact member 24 causing the hook 29 to slip past the rear end of the insulating block 30, whereupon the spring 27 will force the hook 29 downwardly back of the block and into contact with the companion contact member 31, thus establishing a closed circuit including the battery 9 and the lamp 10. The lamp 60 65 will thereupon be illuminated and call the at-

tention of those within view of the lamp to the fact of an accident. The parts will remain in the interlocked condition shown in Figure 3, until the movable contact member 24 is manually raised. This may be accomplished by 70 grasping a button or handle 38 shown as provided on the contact for this purpose. The inherent resiliency of the buffer 11 will restore the buffer, the rod 23 and the movable contact member 24 to normal position, but the lamp 75 will remain lighted until this manual lifting of the movable contact is performed.

Of course a horn, bell or other audible or visual signal might be substituted for, or used in addition to, the lamp 10 and any source of current might be provided other than a storage battery. The buffer is shown as connected to extension frames 18 and 19 carried upon the front end of the chassis but it is apparent that the buffer might, if desired, be affixed directly to the front ends of the channel beams or other parts of a chassis. 80 85

The contact piece 31 will preferably be of a length equal to the space between the radiator and the buffer in normal position. 90

It is obvious that various changes and modifications may be made in the details of construction and design of the above specifically described embodiment of my invention without departing from the spirit thereof. 95

What is claimed is:—

1. A fender circuit closing mechanism comprising a fixed contact, a block of insulating material on said fixed contact having a beveled face, a movable contact cooperating with 100 said fixed contact and having a hook normally resting on said block and inclined to lock with said beveled face, a guide for the movable contact, and yieldable means acting against the guide and movable contact to urge the hook toward the fixed contact. 105

2. A signal circuit closing mechanism comprising a fixed contact plate, a block of insulating material secured upon the end portion of said fixed contact plate and having its inner edge beveled from the plate downwardly and outwardly, a movable contact plate cooperating with said fixed contact plate and having a hook on the end portion thereof disposed at substantially an acute angle to the plate and adapted to ride over the insulating block and to snap behind the block and make contact with the fixed contact plate and be locked behind said beveled face of the insulating block, a guide for said movable contact plate, and a bow spring between said guide and movable contact plate for urging the contact plates together. 110 115 120

In testimony whereof I affix my signature.
GEORGE F. EGAN. 125
